UNITED STATES PATENT OFFICE.

WILLIS H. CARRIER, OF BUFFALO, NEW YORK, ASSIGNOR TO BUFFALO FORGE COMPANY,
OF BUFFALO, NEW YORK.

HYGROSTAT OR THERMOSTATIC DEVICE.

1,138,082.

Specification of Letters Patent.

Patented May 4, 1915.

Application filed May 26, 1910, Serial No. 563,509. Renewed February 20, 1914. Serial No. 820,065.

To all whom it may concern:

Be it known that I, WILLIS H. CARRIER, a citizen of the United States, residing at Buffalo, in the county of Erie and State of New York, have invented a new and useful Improvement in Hygrostats or Thermostatic Devices, of which the following is a specification.

- This invention relates more particularly to improvements in hygrostats or thermostatic instruments, the action of which is dependent upon both the temperature and the hygrometric condition of the surrounding atmosphere.
- An instrument of this character is disclosed in the application for United States patent filed by myself and E. W. Comfort September 28, 1908, Serial No. 455,208, which comprises two expansible or thermostatic elements, one influenced by the actual or dry bulb temperature of the air and the other influenced by the lower wet bulb temperature of the air produced by evaporating moisture in its vicinity, and a humidity regulating device which is actuated by the differential action of said expansible elements. The fluctuations in the dry and wet bulb temperatures of the air, which take place while the percentage of humidity remains constant, bear a practically fixed relation or ratio to each other within ordinary ranges of temperature, but the radios differ for different per cents of humidity. Likewise, the ratio of fluctuations in the dry and wet bulb temperatures of the air remains practically constant for the same absolute humidity but differs for different absolute humidities. In the instrument disclosed in said application the expansible elements have the same coefficients of expansion and actuate the regulating device through a lever mechanism which can be adjusted so that the two elements will act on the regulating device with leverages which have different ratios or relations to each other corresponding to different ratios of changes in the dry and wet bulb temperatures of the air, whereby the instrument can be set to produce different desired hygrostatic conditions.
- The object of this invention is to produce an accurate and reliable hygrostat or thermostatic instrument of the nature stated, which is of simple and practical construction and which can be quickly and easily set to produce different required results by

the actuation of a single adjusting screw or device.

The instrument hereinafter described is primarily intended for regulating the humidity of the air, but the invention is not necessarily restricted to humidity regulating instruments, as the motion of the device actuated by the thermostatic elements can be utilized through suitable instrumentalities for effecting different desired results.

In the accompanying drawings, consisting of three sheets: Figure 1 is a front elevation, partly broken away, of a hygrostat embodying the invention. Fig. 2 is a horizontal section partly in plan thereof. Fig. 3 is a fragmentary front elevation, partly in section thereof, on an enlarged scale, showing the indicator. Fig. 4 is a fragmentary longitudinal sectional elevation thereof, on an enlarged scale. Fig. 5 is a transverse sectional elevation thereof, on an enlarged scale, in line 5—5, Fig. 1. Fig. 6 is a transverse sectional elevation thereof on an enlarged scale, in line 6—6, Fig. 2. Fig. 7 is a detail section in line 7—7, Fig. 4. Fig. 8 is a fragmentary perspective view of the connecting lever for the expansible elements and associated parts.

Like reference characters refer to like parts in the several figures.

A and B represent the two thermostatic or expansible elements which are respectively subjected to the actual, or dry bulb, and the wet bulb temperatures of the air (suitable provision being made for evaporating moisture in the vicinity of the element B) and which operate in opposition to each other on a regulating device or lever C, as herein-after described.

For convenience in description, the two elements A and B are hereinafter termed the "dry" and "wet" elements, respectively. One element, preferably the wet element B, may consist of a single tube or piece of hard rubber or other suitable material having a high coefficient of expansion. The other, or dry element, as shown in Fig. 4, consists of a tube A' of similar material having a high coefficient of expansion, and a rod A² which has such a low coefficient of expansion that it is relatively non-expansible. This rod is screw-threaded and works in a stationary non-expansible nut a and has an end portion which is screwed into an internal screw-thread in the tube A', so that by screwing

the rod A^2 into or out of the tube the effective expansible length of the tube is decreased or increased and the coefficient of expansion of the whole element, consisting of the two parts A' and A^2 , is changed. The nut a preferably has a guide cavity provided with an insulating ring a' in which the adjacent end of the tube A' bears and is adapted to slide freely, while being held from turning by a key a^2 . The nut also has a guide extension a^3 in which a smooth portion of the rod A^2 bears and is guided, whereby the two parts of the dry element are properly supported and guided. The screw rod could be turned by a finger wheel or part at its outer end, but preferably a finger wheel a^4 is employed having a shaft a^5 which is splined in the outer end of the screw A^2 . The finger wheel shaft a^6 is journaled in a bearing a^5 on the casing D of the instrument and is held from endwise movement therein, as by a screw a^7 extending into a circumferential groove in the shaft a^6 so that the wheel or handle a^4 for the screw A^2 does not move lengthwise with the screw when it is turned.

In the construction shown, the two expansible elements are arranged parallel with each other with one end of the wet element bearing by a point or reduced part b against the regulating lever or device C , while the opposite end of the element and the free end of the dry element bear against a pivoted lever or member E which is held against the ends of the two elements by a suitable spring F . The regulating lever or device C preferably consists of two parts independently fulcrumed to posts or parts c of the casing D respectively by thin spring plates c' c^2 which hold the two parts of the lever in contact and press the lever against the wet element. The lever or member E , as shown in Figs. 4 and 8, has two fulcrum points e and e' which are held by the spring F in sockets in a wall or part f of the casing D , a socket in which a point e^2 on the end of the dry element A bears, and an adjustable screw e^3 having a pointed end which bears in a socket on the end of the wet element. The spring F , which is connected at opposite ends to the lever E and to a wall or part f' of the casing, draws the lever E toward the expansible elements A and B but permits the lever to be moved in the opposite direction by the expansion of the elements. The regulating lever or device C will remain stationary or be moved in one direction or the other, depending upon the relative changes in the lengths of the two expansible elements caused by changes in the temperatures affecting them.

If the screw-thread of the adjustable part A^2 and the internal thread of the part A' of the dry element were of the same pitch at all times, regardless of the change in

length of the part A' due to the expansion and contraction thereof at different temperatures, the coefficient of expansion of the compound dry element would be changed by screwing the part A^2 into or out of the other part without any change in the effective expansible length of the dry element. But the pitch of the thread of the part A' changes with the expansion and contraction of this part, and since the wet bulb depression is different for different percentages of humidity at the same dry bulb temperature, the relative lengths of the wet and dry elements will be different for different percentages of humidity. Therefore, when the relative coefficients of expansion of the elements are changed by adjusting the screw A^2 to obtain a desired percentage of humidity, the relative lengths of the wet and dry elements must also be appropriately changed in order to obtain the proper regulating action of the lever or device C . By cutting the threads of the parts A' and A^2 to such a difference of pitch that the ratio of the two pitches at any temperature is practically the same as the ratio to each other of the wet and dry bulb temperatures, as reckoned from a predetermined fixed point or zero, which is dependent upon the relative expansibility of the elements, then at normal temperatures, for example, between 50° and 100° Fahrenheit, the adjustment of the part A^2 more or less into or out of the part A' will change the relative expansive lengths of the two elements to the extent required for different percentages of humidity as well as changing the ratio of expansion of the elements. When one part of the compound element A is relatively nonexpansible, as stated, the screw threads should be such as to have the same pitch at approximately 4° above zero Fahrenheit.

The adjustment of the relative lengths of the wet and dry elements could be effected by adjusting the bearing screw e^3 carried by the lever E , but by constructing the dry element as above described the turning of the single adjustable part A^2 adjusts for both the expansive length and the expansive ratio of the elements at one and the same time. Furthermore, the adjustable part A^2 of the dry element has sufficient travel to allow the adjustments for various percentages of humidity to be indicated accurately upon a dial.

The lever or device C could be differently constructed and mounted, and means of other construction could be employed for operatively connecting the two expansible elements constructed as described. The free end of the regulating lever C acts as a valve to control a bleeder or escape orifice h , Figs. 4 and 7, in a branch h' of a pipe H which supplies compressed air to the actuating diaphragm or motor of the apparatus (not

shown) which regulates the humidity of the air. A restricting valve h^2 is provided in the air pipe H which permits only a very small quantity of air to pass to the regulating motor.

5 If the bleeder orifice is closed by the regulating device C the air passing the restricting valve to the motor will operate the motor to move the part actuated thereby in one direction, where as if the regulating device C is moved to open the bleeder orifice the air will escape from the dia-

10 phragm through the orifice faster than it can pass the restricting valve to the motor, thus permitting the motor to effect an op-

15 posite movement of the part actuated thereby. Thus the regulating device C by opening and closing the bleeder orifice h acts, through the humidity regulating apparatus, to effect a change in the humidity of the air.

20 The invention is not restricted to the means described whereby the movement of the regulating lever C effects the regulation, and other instrumentalities governed by the movement of the lever C , or other part similarly actuated, can be employed for producing a desired result.

The means shown for causing the wet element to be affected by the wet bulb temperature of the air consists of an absorbent wick I which surrounds the wet element and dips into water in a receptacle i which is automatically replenished, as the water is taken up by the wick, from a water reservoir i' formed by a large chamber in the rear portion of the casing D . Water can be supplied to the reservoir i' and fed automatically therefrom to the receptacle i in any usual or suitable way, for example, as described in said application.

40 The expandable elements A and B are preferably located in an air passage formed by the walls f and f' of the casing D and connecting walls h h' , and air is caused to circulate through this passage by an aspirator or other means to insure an active evaporation of the moisture around the wet element.

45 Other suitable means could be used for subjecting the wet element B to the wet bulb temperature of the air.

50 L represents a pointer or index which operates with a dial l for indicating the correct adjustments of the instruments for different percentages of humidity. This index, in the construction shown, is pivoted in the rear portion of the casing D and is connected by a link l' to a rod l^2 which slides in a guide tube l^3 . This rod is provided at one end with an adjustable screw l^4 which is held against a collar on the adjustable part A^2 of the dry element by a spring l^5 acting on the index. The index is shifted with the adjustable part A^2 of the dry element and by its position indicates the percentage of humidity for which the instrument is set. Any

other suitable means actuated by the adjustment of the part A^2 could be employed for this purpose.

I claim as my invention:

1. In a thermostatic instrument of the character described, the combination of two expansible elements which are subject to different temperatures, a single adjustable part, by the adjustment of which both the relative expansible length and the expansive ratio of said elements are changed simultaneously, and a device which is actuated by the differential action of said two elements, substantially as set forth.

2. In a thermostatic instrument of the character described, the combination of two expansible elements which are subject to different temperatures and one of which comprises two parts which have different coefficients of expansion and have a screw connection, a support with which one of said parts has a screw connection, said screw connections having threads which have the same pitch at a temperature approximately four degrees above zero Fahrenheit, and a device actuated by the differential action of said two elements, substantially as set forth.

3. In a thermostatic instrument of the character described, the combination of two expansible elements which are respectively influenced by the dry and wet bulb temperatures of the air, one of said elements consisting of a differential screw, the parts of which have different coefficients of expansion, the ratio of the pitches of the threads of said differential screw being practically the same as the ratio to each other of the wet and dry bulb temperatures as reckoned from a predetermined zero, and a device actuated by the differential action of said two expansible elements, substantially as set forth.

4. In a thermostatic instrument of the character described, the combination of two expansible elements, means whereby one of said elements is subjected to the wet bulb temperature of the atmosphere, a single adjustable part by the adjustment of which the relative expansible lengths and the expansive ratio of said elements are changed simultaneously, and a device which is actuated by the differential action of said two elements, substantially as set forth.

5. In a thermostatic instrument of the character described, the combination of two expansible elements, means whereby one of said elements is subjected to the wet bulb temperature of the atmosphere, one of said elements comprising two parts having different coefficients of expansion, a support for said two-part element, one part of said element being adjustable and having screw connections with said other part of the element and with said support, the threads of said screw connections having pitches such

that the adjustment of said adjustable part changes the relative expandable lengths and the expansive ratio of said elements simultaneously, and a device which is actuated by 5 the differential action of said two elements, substantially as set forth.

6. In a thermostatic instrument of the character described, the combination of two 10 expandable elements which are subject to different temperatures and are arranged substantially parallel with each other, one of said elements comprising two parts which have different coefficients of expansion and have a screw connection, a support with 15 which one of said parts has a screw connection, a lever which bears against the free end of said two-part element and against the adjacent end of the other element, and a device which bears against the opposite 20 end of said last mentioned element and is actuated thereby, substantially as set forth.

7. In a thermostatic instrument of the character described, the combination of two 25 expandable elements, means whereby one of said elements is subjected to the wet bulb temperature of the atmosphere, one of said elements comprising two parts having different coefficients of expansion, a support for said two-part element, one part of said 30 element being adjustable and having screw connections with said other part of the element and with said support, the threads of said screw connections having pitches such that the adjustment of said adjustable part

changes the relative expandable lengths and 35 the expansive ratio of said elements simultaneously, and a rotatable operating handle for said adjustable part which is held from endwise movement with said adjustable part, substantially as set forth.

8. In a thermostatic instrument of the character described, the combination of two 40 expandable elements, means whereby one of said elements is subjected to the wet bulb temperature of the atmosphere, one of said 45 elements comprising two parts having different coefficients of expansion, a support for said two-part element, one part of said element being adjustable and having screw connections with said other part of the element and with said support, the threads of said screw connections having pitches such that the adjustment of said adjustable part 50 changes the relative expandable lengths and the expansive ratio of said elements simultaneously, a device which is actuated by the differential action of said two elements, and an index which is connected to and moves with said adjustable part for indicating the 55 adjustment thereof, substantially as set forth.

Witness my hand this 23rd day of May, 1910.

WILLIS H. CARRIER.
